UNITED STATES PATENT OFFICE.

EDWIN Y. JUDD, OF HARTFORD, CONNECTICUT.

MILK-JAR.

SPECIFICATION forming part of Letters Patent No. 353,069, dated November 23, 1886.

Application filed September 8, 1886. Serial No. 213,008. (No model.)

To all whom it may concern:

Be it known that I, EDWIN Y. JUDD, residing at Hartford, in the county of Hartford and State of Connecticut, have invented certain new and useful Improvements in Milk-Jars; and I do declare the following to be a full, clear, and exact description of the same, reference being had to the accompanying drawings, which form a part of this specification.

10 My invention relates to an improvement in milk-jars, the object being to provide them with improved sealing attachments of simple, durable, and inexpensive construction, easy and rapid operation, and of a high degree of efficiency in use.

With these ends in view my invention consists in certain details of construction and combinations of parts, as will be hereinafter described, and pointed out in the claims.

20 In the accompanying drawings, Figure 1 is a view in side elevation of a milk-jar embodying my invention, with the stopper in position for sealing it. Fig. 2 is a similar view with the stopper, yoke, and ring turned preparatory to unsealing the jar. Fig. 3 is a similar view with the stopper removed from the mouth of the jar, and allowed to hang at one side. Fig. 4 is a view of the jar in transverse section on the line *a a* of Fig. 1, and showing the relative positions of the cam and vertical slots. Fig. 5 is a detached view in elevation of the stopper and yoke, and Fig. 6 is a detached view in perspective of the ring.

30

The jar *A* and the neck *B* thereof may be 35 of any suitable form and construction. Under my invention the neck *B* is provided with two horizontally-inclined cam-slots, *C C*, respectively located upon its opposite faces, with two vertical slots, *D D*, leading into the upper ends of the cam-slots, and with a conical or cam face, *E*, extending around the neck, larger in diameter at its upper than at its lower edge, and located just above the said cam-slots. The stopper *F* may also be of any 40 suitable form and construction, and is provided upon its upper face with a lug, *G*, having a horizontal perforation, *H*, as shown.

The yoke is made of wire, and consists of a cross-piece, *I*, and arms *J J*, having inwardly-bent ends *K K*, the cross-piece passing through the perforated lug of the stopper, and the bent

ends of the arms entering the slots in the neck of the jar.

The ring *L* is simply a metallic band provided at opposite points with perforations *M M*, through which the ends *K K* of the yoke respectively pass before they enter the slots.

To seal the jar the stopper is placed upon the mouth of its neck, and the yoke and the ring pushed down to cause the ends *K K* of the yoke to enter the upper ends of the cam-slots. The stopper, yoke, and ring are then turned to draw the stopper down upon its seat, whereby the jar is sealed. To open the jar, the said stopper, yoke, and ring are turned to bring the ends *K K* into the upper ends of the cam-slots, and hence into alignment with the vertical slots. The said parts are now lifted through the upward range of such vertical slots, whereby the stopper is so far carried above the mouth of the jar that it will clear the same in being swung aside, as shown in Fig. 3 of the drawings. The lifting of the ring, as described, engages it with the cam-face of the neck, by virtue of which engagement it is held together with the yoke in its elevated position, facilitating the handling of the stopper in swinging it away from and over the jar by preserving the clearance between the neck of the same and the stopper. The cam-slots take up or compensate for distortion or bending of the yoke, resulting from the use of the jar, and for any inequalities or defects in the packing, which is placed between the stopper and its seat before sealing the jar.

85 The ring, aside from its function of holding the yoke in an elevated position, as described, protects the arms from being bent and preserves their right relations.

My improved sealing attachment is very 90 readily and rapidly operated, durable and efficient in use, and capable of being cheaply made.

Having fully described my invention, what I claim as new, and desire to secure by Letters Patent, is—

1. A milk-jar provided with cam-slots, a stopper, a yoke attached thereto and entering the slots, a ring fitting over the neck of the jar and having the yoke connected with it, and means located above and engaged by the ring for temporarily supporting the same in

an elevated position, permitting the stopper to clear the neck of the jar in being swung away from or over the same, substantially as set forth.

5 2. A milk-jar provided with cam-slots and a cam-face, a stopper, a yoke attached thereto and entering the slots, and a ring fitting over the neck of the jar and having the arms of the yoke connected with it, and engaging when elevated with the cam-face of the jar, substantially as set forth.

3. A milk-jar provided with cam-slots, and with a cam-face encircling its neck, larger in diameter at its upper than at its lower edge,

5 and located above the said slots, a stopper, a yoke attached to the same and entering the slots, and a ring fitting over the neck of the jar and having the yoke connected with it, and engaging when lifted with the said cam-face of the jar, substantially as set forth.

4. A milk-jar provided with two cam-slots, respectively located on opposite sides of its neck, with two vertical slots respectively leading into the upper ends of such cam-slots, and with a cam-face located above the cam-slots, 25 a stopper, a yoke carrying the stopper and having the lower ends of its arms bent to enter the slots in the jar, and a ring fitting over the neck of the jar and connected with the arms of the yoke in position to engage with the 30 cam-face of the jar, substantially as set forth.

In testimony whereof I have signed this specification in the presence of two subscribing witnesses.

EDWIN Y. JUDD.
